UNITED STATES PATENT OFFICE.

LOUIS R. YANSKY, OF CHICAGO, ILLINOIS.

EXTENSIBLE GAS-FIXTURE.

No. 892,639.

Specification of Letters Patent.

Patented July 7, 1908.

Application filed April 25, 1906. Serial No. 313,633.

To all whom it may concern:

Be it known that I, LOUIS R. YANSKY, a citizen of the United States, residing at No. 4 De Kalb street, in the city of Chicago, county 5 of Cook, and State of Illinois, have invented a new and useful Improvement in Extensible Gas-Fixtures, of which the following is a specification.

My invention relates to that class of gas 10 fixtures which are used in dwellings and which are designed for lighting purposes, and which, being adapted to be supported in ceiling of room, can be raised, lowered and adjusted at pleasure at any vertical position be- 15 tween the floor and ceiling of the room.

The object of my invention is to provide a 20 combined extensible gas light and heating fixture, which can be adjusted close to the ceiling when not in use, and which may be drawn down and adjusted near the floor when used especially for heating purposes, or be adjusted at any intermediate point be- 25 tween these extreme positions. The manner in which I accomplish this object is described in the following specifications and illustrated in the accompanying drawings in which:

Figure 1 is a front elevation of my extensible combined gas light and gas heating fixture adjusted as to height, for ordinary light- 30 ing purposes. Fig. 2 is a side elevation, the relative positions of the parts being the same as in Fig. 1. Fig. 3 is a central sectional view of one of the gas joints. Fig. 4 is a cross section on the line 4—4 Fig. 3. Fig. 5 is a cross 35 section on the line 5—5 Fig. 3. Fig. 6 is a cross section on the line 6—6 Fig. 3. Fig. 7 is a longitudinal sectional view of the adjustable shade holder bracket, disconnected from the fixture.

40 In the drawings A is a wood screw pro- vided with a ceiling plate A¹. This screw is adapted to be affixed in a ceiling joist and to thereby support the gas fixture. Affixed on the head A² of this screw is a coiled spring B. 45 Permanently affixed in the other end of this spring is a coupling C. The end of the head A² and the end of the coupling C are spaced from each other in said spring to allow a considerable lateral movement of the fixture and 50 to thereby prevent the breakage of the fixture by lateral pressure applied thereto by using or otherwise.

In one side of the coupling C a supply pipe C¹ is affixed, this pipe being adapted for the 55 attachment thereto of a flexible tube C² the other end of which is attached to the burner

of any ordinary permanent gas fixture in the room. The supply of gas passes through the pipe C¹ and gas way in the coupling C into the joint D of which the coupling C forms the 60 middle part D¹. In the fixture as shown there are seven of these joints. Each of these joints is constructed of the following parts: the central part D¹, two end parts D² and D³, a connecting pivotal rod D⁴, washers 65 D⁵, lock nuts D⁶ and end caps D⁷.

The parts D¹, D², and D³ are cylinders through which the rod D⁴ extends. The interior diameters of these cylinders are adapted to permit the free flow of gas around the rod, 70 and the exterior diameters are sufficient to allow of sufficient material to support the connecting parts of the fixture. The center part D¹ may either form an integral part of the coupling C, or be constructed with a 75 threaded aperture D⁸ shown by the dotted circle in Fig. 3 and in section in the ends D² and D³ Fig. 3. Each of these ends has an external threaded part D⁹, adapted to support a cap D⁷, these caps being adapted to 80 cover the ends of the rod D⁴, lock nuts D⁶, and washers D⁵ and together with the washers and nuts to form gas tight ends to the joint D. These several joints are connected together with gas tubes E which form a 85 quadruple toggle joint through which the gas flows, and by which the fixture may be adjusted near the ceiling and be drawn down till the tubes E are in a vertical position, the length of these tubes limiting the distance 90 the burner can be lowered from the highest point at which it is adjusted when the fixture is closed against the ceiling. The friction between the several parts of the joint D is adjusted by the lock nuts and washers on 95 the rod D⁴ and the lower part of the fixture is thereby sustained at any desired point. Supported in the central part of the lowest joint D is a pendent gas pipe F, on which a handle F¹ is affixed; below this handle on the 100 pipe F is an adjustable sleeve G, adapted to support an adjustable arm G¹; this arm is formed of two strips of metal, arranged parallel to each other and connected by bolts and thumb screws G². One of these bolts 105 and screws passes through the lips of the sleeve G and closes the sleeve on the pipe F; the other bolt and screw passes through a bracket H which is thereby attached to and adjustably supported in said arm G¹. Affixed to this bracket is a shade I. Connected to the pendent pipe F by an elbow J is

a horizontal pipe K adapted to support a gas burner L.

What I claim as new and desire to secure by Letters Patent, is:

- 5 1. In a gas fixture of the kind described, the combination of the following parts constructed and connected as described—to wit—a coiled spring; means for securing said spring pendently to a ceiling; a coupling af-
10 fixed to the free end of said spring; a series of rotatable joints, each of said joints being composed of three cylindrical members, a threaded center pin extending through said members, washers and lock nuts secured on
15 said pin adapted to hold said members together, said coupling constituting the central member of one of said joints; a pair of caps secured on the ends of each of said joints; a series of tubes affixed to and connecting said joints as described and illus-
20 trated; an L shaped tube affixed to the center member of one of said joints and a burner attached to the end of said tube, said coupling, joints and tubes forming an extensible
25 gas way; a bracket supported on said L shaped tube; means for adjustably attaching said bracket to said tube; and a shade at-
tached to said bracket.

2. In a gas fixture of the kind described,

the combination of a coiled spring and means 30 for securing said spring pendently to a ceiling, with a coupling, a series of joints each being composed of three members rotatably secured on an axial rod extending through said members, an axial rod extending through said members, washers and nuts secured on said rods adapted to hold said members together, caps on the ends of said joints, a series of tubes secured to and connecting said joints, a pendent tube affixed to one of said joints, a burner 40 secured on said tube—a bracket supported on said pendent tube and a shade supported on said bracket.

3. In a gas fixture of the kind described, the combination consisting of a coiled spring 45 adapted to be pendently attached to a ceiling; a coupling affixed to said spring; a series of joints, said coupling forming the center member of one of said joints; a series of tubes affixed to and connecting said joints; a tube 50 affixed to the center member of one of said joints; a burner attached to said tube and a bracket and shade supported on said tube as described.

LOUIS R. YANSKY.
